(57) **CLAIM**

The ornamental design for an illumination device, as shown.

DESCRIPTION

FIG. 1 is a perspective view of an illumination device showing our new design.

FIG. 2 is a front elevational view thereof.

FIG. 3 is a rear elevational view thereof.

FIG. 4 is a left-side, elevational view thereof.

FIG. 5 is a right-side, elevational view thereof.

FIG. 6 is a top plan view thereof.

FIG. 7 is a bottom plan view thereof.

FIG. 8 is a perspective view thereof when the illumination device is in a first state; and,

FIG. 9 is a perspective view thereof when the illumination device is in a second state.

1 Claim, 9 Drawing Sheets

FIG. 1

FIG. 2

FIG. 3

FIG. 4

FIG. 5

FIG. 6

FIG. 7

FIG. 8
